UNITED STATES PATENT OFFICE.

FEDKO FEDZYNA, OF NEW YORK, N. Y.

FLYING-MACHINE.

1,308,175.

Specification of Letters Patent.

Patented July 1, 1919.

Application filed October 22, 1918. Serial No. 259,217.

To all whom it may concern:

Be it known that I, FEDKO FEDZYNA, a citizen of Russia, residing at New York, county of New York, and State of New York, have invented certain new and useful Improvements in Flying-Machines, of which the following is a specification.

This invention relates to improvements in aeronautic apparatus and particularly to 10 "heavier than air" types.

The principal object of the invention is to provide an apparatus with a motor by which the apparatus is driven through the air, the motor also being engageable with the driving wheels at the front of the apparatus, whereby it is caused positively to move over 15 a level surface preliminary to rising in the air.

A further object is to combine with the 20 apparatus means whereby a raising effect may be obtained so that the run prior to ascension may be materially decreased in its extent.

These and other like objects, which will 25 become more fully manifest as the description progresses, are attained by the novel construction and combination of parts hereinafter described and shown in the accompanying drawings, forming a material part 30 of this disclosure, and in which:—

Figure 1 is a top plan view showing a flying machine made in accordance with the invention.

Fig. 2 is a longitudinal sectional view of 35 the same taken substantially on the center line.

Fig. 3 is a front plan view thereof, and

Fig. 4 is an enlarged vertical sectional view taken on line 4—4 of Fig. 1.

The car 10 of the aeroplane is essentially 40 rectangular in cross section, having sides 11, joined with a curved bottom 12, and a partial cover 14, the front of the car being closed by a plate 15. An opening 16 is 45 formed through the cover at the back of the car in which the operator may rest upon a seat 18, extending from the inclined back 19 which forms the rear wall of the car and from which extend oppositely disposed lateral blades 20, gradually tapering toward 50 the rear as do the vertical blades 21 and 22, respectively above and below the lateral blades 20.

The side blades 20 terminate in semi-circular elements 23 in which, pivoted on a pin 24, is a leaf 25, which can swivel side-

wise on a vertical axis in the manner of a hinge therein. A hinge 30 has one element secured to the leaf 25 and another element attached to the narrow front end of a triangular wing 31. Rigidly secured on the lower semi-circular element 23 is a bracket 33, its lower end forming bearings 34, for a shaft 35, upon which is journaled the rear landing wheel 36.

On the upper side of the triangular wing 31 is a vertical blade 38, and rigidly secured at the upper end of the pins 24 is a transverse bar 40, having attached to its opposite ends cables, respectively 41 and 42 (see Fig. 70 1), the same extending through openings formed in the plate 19, and engaged upon drums 43 and 44 fixed on a transverse spindle 45 journaled in the sides 11 of the car.

Set in the vane 31 is another transverse 75 bar 47 and engaged at its ends are cables 48 and 49, passing below the lateral blades 20 on each side and over pulleys 52 attached to the bottom of the car, finally engaging with drums 50 on the spindle 45, thus providing 80 means for actuating the wing or rudder 38.

Centrally on the spindle 45, is a hand wheel 46, by means of which the operator in the seat 17 can readily turn the aeroplane 85 in any desired direction.

The horizontal blade or rudder 31 is moved up and down upon the hinge 30, by means of a cable 55, the same extending toward the front and connected with a lever 90 56 pivoted to the car upon a pin 58, extending through the sides of the car the lever having a spring 59 for raising it, the lever being convenient of access by the operator.

From the foregoing it will be seen that all 95 of the several steering devices are under the ready immediate control of the person seated within the car.

In the front portion of the car is an engine 62, driving a shaft 63, which extends 100 through the front 15 of the car and has rigidly engaged with it a hub 64 carrying the propeller blades 65.

The weight of the aeroplane, when upon 105 the ground, is partially taken upon a pair of front driving wheels 68 mounted upon a shaft 69, carried in supports 70 extending down from the car, the supports having side braces 71 and front and rear braces respectively 72 and 73. Fixed upon the shaft 69, 110 are sprocket wheels 75, over which are trained chains 76, engaging with other

sprockets 77, fixed upon a transverse shaft 78, journaled in the sides of the car, and having at its center, a bevel gear 80 meshing with a mating gear 81, fixed upon the 5 shaft 63.

Fixed upon the shaft 78 besides the sprocket 77 are other sprocket wheels over which are trained chains 85, connecting with other sprocket wheels 86, fixed upon the 10 shaft 87, and also fixed upon the shaft 78, are another pair of sprockets over which are chained chains 88, running over sprocket wheels 89, fixed upon the ends of shafts 90, mounted in a circular support 91, held in a 15 rigid position by the lateral braces 93 at the front and rear braces 94.

Fixed centrally upon the shafts 90, are a plurality of pairwise arranged plates 95 having between them vertical plates 98 constituting substantially box-like planes, adapted to produce when rotated a lifting 20 effect upon the structure, causing it to rise in the air, it being understood that when the blades 96 are rotated, the front landing 25 wheels are also revolved, giving it an impulse forward and upward at the same time, which in addition to the effect of the propeller blades 65, raise the entire structure in an effective manner.

30 The shaft 78 is controlled by operating a clutch lever 100, movable within the brackets 101, by means of which the gears may be engaged or disengaged from operative relation with the shaft 63.

35 Extending out from the sides of the car 10, are a pair of planes 105 and 106, respectively upper and lower, these planes being held rigidly together by vertical posts 107 at their ends, while another series of vertical 40 posts 108 pass through the main planes 105 and 106 connecting them together at a point

inward from the outer rods 107 and connected with their outstanding ends are the braces 71 and 72 respectively, while fore and aft braces 110 and 111 connect between the 45 posts 108, and the front of the car 10 and the vertical blades 21 and 22 at a point beyond the body of the car.

From the foregoing it will be seen that all of the several controls, starting, stopping, 50 raising, and directing, either vertically or horizontally, are under the immediate and ready control of an operator without leaving the seat and that the plates 95 and 96, in addition to the rotatable landing wheels, 55 form novel and practical means tending to improve the performance of the machine.

Having thus described my invention, what I claim as new, and desire to secure by Letters Patent, is:—

60 In an aeroplane of the character described, a car, a motor contained therein, a propeller actuated by said motor, substantially box-like lifting planes above said car, a horizontal rudder pivotally engaged at the rear 65 of said aeroplane, a vertical rudder fixed upon the upper sides of said horizontal rudder, a transverse shaft in said car, cable drums on said shaft, a hand wheel for operating said shaft, and cables connecting 70 said drums and said rudders for operating the same, levers pivoted to the car, springs controlling said levers, and cables secured to said levers and the horizontal rudder, means for operating said lifting planes from the 75 motor, brackets in said car, and a clutch lever sliding in said brackets for controlling said means for operating the lifting planes from the motor.

76 In testimony whereof I have affixed my 80 signature.

FEDKO FEDZYNA.
